UNITED STATES PATENT OFFICE.

FREDERICK G. MUSSO, OF SAN JOSE, CALIFORNIA.

COLLAPSIBLE CAMP STRUCTURE.

1,244,760.

Specification of Letters Patent. Patented Oct. 30, 1917.

Application filed May 2, 1917. Serial No. 165,888.

To all whom it may concern:

Be it known that I, FREDERICK G. MUSSO, a subject of the King of Italy, and resident of San Jose, in the county of Santa Clara and State of California, have invented certain new and useful Improvements in Collapsible Camp Structures, of which the following is a specification.

My invention relates to a collapsible structure which provides a bed and, when desired, a dressing room, and it is the object of my invention to provide a structure of the nature indicated that may be easily stored in a small space, easily transported as on the running-board of an automobile, easily assembled, and simple and economical to manufacture.

In the accompanying drawings in which similar characters of reference refer to similar parts throughout the several views,

Figure 1 is a perspective view of the assembled structure ready for use.

Fig. 2 is an enlarged perspective view of a typical corner construction, parts being broken away.

Fig. 3 is an illustration of the method of stretching the bed spring and securing the same after stretching.

Fig. 4 is a detail perspective illustrating the method of mounting the supporting bars to the corner uprights, parts broken away.

Fig. 5 is a detail elevation of the joint used in the dressing-room frame.

In the drawings the corner member is shown as consisting of a main body portion 1 having a socket 2 formed therein to receive leg 3, stops 4 being cast integrally in the upper portion of its interior surface to prevent the upper end of leg 3 from passing clear through, and provided with holes 5 for the purpose hereinafter described. On the outer portion of body portion 1 is cast another portion 6 having socket 7 formed therein to receive the lower end of corner pole 8 and having stops 9 cast in the lower portion of its inner surface to prevent the lower end of pole 8 from passing clear through. On the inside of portion 1 lengthwise of the bed is cast another portion 10 having a socket 11 formed therein to receive one end of rail 12. The spring used in this instance consists of a suitable wire mesh 13 attached to end pieces 14 and 15

respectively by coil springs 16 and 17 respectively, end pieces 14 and 15 being in the form of angle irons. The connection of each angle iron to the four corners of the structure is the same and is illustrated in Fig. 2, in which end piece 14 is shown provided with holes 14^a and 14^b adapted to be placed in alinement with holes 5 in body portion 1, and engaging bolts 18 which securely hold the parts together. Each of the side rails 12 is made in two pieces fastened together at their abutting ends by a hinge 19 positioned as shown. A channel iron 20 is securely fastened to one end of one of the sections of rail 12 by bands 21 and projects past the end thereof to engage the abutting end of the other portion of rail 12, the two parts being held in rigid alinement by a collar 22 positioned on rail 12 and sliding over said projecting end of channel iron 20.

On the upper end of each corner pole 8 is provided a pin 23 adapted to engage a hole 24 formed near the end of cross pieces 25, cross pieces 25 being two in number one at each end of the bed structure.

In connection with the structure hereinbefore described I provide a dressing room in the following manner: At 26 I provide a pair of bars, each bar having a pin as 27 formed on each end thereof, the pin on one end being adapted to engage a hole 28 formed in corner pole 8, and the pin on the other end being adapted to engage a hole 29 formed in cross-bar 30 and near the end thereof.

In order to stiffen the whole structure when erected, braces 31 are provided as shown, each brace being pivotally connected to a rail 12 as at 31^a, and having a hole 32 formed in its outer end adapted to engage a pin 33 positioned in leg 3.

When the structure is to be assembled the bundle is unrolled and the springs laid out flat upon the ground but upside down as shown in Fig. 3. The four corner members 1 are now bolted to end pieces 14 and 15 respectively, and of course are also inverted. Side rails 12 are now positioned as indicated in dotted lines in Fig. 3, the relaxed position of corner members being indicated by the short, vertical dotted lines shown at the outer ends thereof, and sufficient pressure applied to bring the two parts into

alinement and force the ends into sockets 11 as shown in solid lines in Fig. 3. Collar 22 is now slipped over channel 20 and springs 5 are held properly stretched for use. Legs 3 10 may now be inserted in sockets 2, the braces 31 positioned with the holes 32 engaging pins 33 and the bed proper reversed and set firmly upon said legs 3. Pins 33 are provided with large heads 34 and so positioned that braces 31 will have to be sprung into position and held by said large heads 34. It now only remains to insert poles 8 in sockets 7, bars 25 on pins 23, and set up bars 26 and 30 as shown and described and the frame is 15 ready to receive its canvas covering 35 and fitted with desirable bedding as 36.

The canvas 35 may be secured in any suitable manner, but I prefer to secure the sides with suitable buttons 37 similar to those 20 used for attaching curtains to automobiles. While the canvas 35 may be arranged in several different ways, I prefer to position it as follows: The top 38 has four side pieces 39—40—41 and 42 positioned and secured as shown and described, the front part being turned back in the illustration. A fifth piece of canvas 43 is attached to the rear end of top 38 and is dropped over bar 30 and held to the ground by pegs as 44. 25 A back 45 for the dressing room is attached to the canvas portion 43 and is carried along between the lower portion of rear legs 3 in the form of an extension 46. A front 47 is attached to the front upper sloping edge of 30 canvas portion 43, the same being shown thrown back in the illustration. It is clear of course that when the dressing room is 35 used as a part of the construction, the canvas portion 40 may be omitted and the top 40 38 continued over bar 30 and to the ground, the said canvas portion 40 being used when no dressing room is desired.

When this structure is taken apart and rolled up the length of the resulting roll is 45 determined by the length of the end pieces 14 and 15, the actual measurement now being used by me being about fifty inches.

While I have herein shown and described a specific means of embodying my invention, 50 it is understood that changes in form, proportions and construction may be made within the scope of the appended claims.

Having thus described my invention, what I claim as new and desire to secure by Letter's Patent, is:—

1. A camp structure comprising a collapsible bed supported a distance from the ground when assembled and having a removable flexible covering positioned thereon, and a collapsible dressing room 60 removably attached to one end thereof and extending to the ground, said dressing room being inclosed with a flexible material on the top and two sides, a curtain door for the third

side and having open communication with 65 said bed on the fourth side, that portion of said fourth side extending from said bed to the ground being inclosed with a flexible material.

2. In a collapsible camp structure, a bed 70 having detachable and foldable side rails, opposite end rails supporting a bed bottom, four corner members, means for detachably securing said side and end rails to said corner members, a removable leg positioned in each corner member, a removable corner pole positioned in each corner member, a cross bar removably positioned on each end 75 pair of corner poles, and a flexible covering removably positioned on said cross bars. 80

3. A corner member for collapsible camp structures, consisting of a body having a socket formed therein adapted to receive a leg, a second socket formed therein and positioned parallel to said first mentioned socket but offset therefrom and adapted to receive a cover-supporting post, a third socket positioned at right angles to said first mentioned socket and in alinement therewith and adapted to receive one end of a side rail, said body being provided with means for securing one end of an end rail thereto. 85

4. In a collapsible camp structure, a bed 90 having foldable side rails, end rails supporting a bed bottom, detachable legs positioned at its four corners, detachable frame work supported from its four corners and a covering for said frame work, and a member for each corner of said bed to which a side rail, 100 end rail, a leg and one member of said frame work are attached, each of said members consisting of a casting having a socket formed therein to receive a leg, and stops for said leg, a second socket positioned 105 parallel with said first mentioned socket but offset therefrom and adapted to receive one end of a member of said frame work, and stops for the same, a third socket positioned at right angles to said first mentioned socket and in alinement therewith and adapted to receive one end of a side rail, and provided with means for securing one end of one of said end rails thereto. 110

5. In a collapsible camp structure, a bed 115 having four corner members, a bed bottom removably attached to said corner members, a leg removably attached to each of said corner members, and a pair of foldable side rails adapted to engage their respective pairs of corner members, and means for locking each of said foldable side rails in extended position. 120

6. In a collapsible camp structure, a bed 125 having foldable side rails, end rails supporting a bed bottom, detachable legs positioned at its four corners, detachable framework supported from its four corners, and a flexi-

ble covering for said framework, a member for each corner of said bed to which a side rail, an end rail, a leg and one member of said framework are attached, a second framework removably attached to said first mentioned framework, and supporting in-closing walls and a top of flexible material

and forming a dressing room provided with a curtain door and having open communication with said bed.

In testimony whereof I have hereunto affixed my signature this 26th day of April, 1917.

FREDERICK G. MUSSO.
